UNITED STATES PATENT OFFICE.

JACOB D. BURGER, OF CHICAGO, ILLINOIS.

SMOKING-PIPE.

1,214,887.

Specification of Letters Patent.

Patented Feb. 6, 1917.

Application filed September 23, 1916. Serial No. 121,708.

To all whom it may concern:

Be it known that I, JACOB D. BURGER, a citizen of the United States of America, and resident of Chicago, Cook county, Illinois, have invented a certain new and useful Improvement in Smoking-Pipes, of which the following is a specification.

My invention relates to smoking pipes of the kind in which the bowl and stump are made of one material, while the stem and mouth-piece are usually composed of some other substance. For example, a very common form of pipe involves a bowl and stump made of brier wood, while the stem and mouth-piece are of rubber vulcanite, amber, celluloid, or some similar material. Wood pipes, however, are liable to burn out, and in addition it is also found that a pipe of this kind will very often become clogged 20 or fouled in the base of the bowl, as is also the case with some other kinds of pipes.

The object of my invention is, therefore, to provide a novel construction and arrangement and combination of materials, such as pipe clay and wood, whereby the bowl of the pipe may be made of wood, preferably cheap or soft wood, without danger of burning out, and with less liability of becoming clogged or fouled in the bottom 30 thereof, thus not only rendering the pipe more safe and less perishable than heretofore, because more sanitary and less liable to burn out than was the case with previous pipes of this general class, but also 35 serving to reduce the cost of manufacture thereof.

To the foregoing and other useful ends, my invention consists in matters hereinafter set forth and claimed.

40 In the accompanying drawings:—Figure 1 is a side elevation of a smoking pipe embodying the principles of my invention, showing the bowl and a portion of the stump in vertical section.

45 Fig. 2 is a horizontal section on line 2—2 in Fig. 1.

As thus illustrated, my invention comprises a bowl A having a stump a, the latter being formed to connect suitably with 50 the stem B of the mouth-piece C, the said stem having a push b which slides into the bore of the stump in the usual and well-known manner. The said bowl and stump are of wood, whereas the stem and mouth-piece are preferably made of rubber vul-

canite, amber, or any of the other well-known materials for this purpose. The bowl has a lining D of pipe clay baked hard before its insertion in the bowl and thereafter fastened in place by means of fire-proof cement, by which is meant any cement that will hold the inner bowl D in place and which will not allow the bowl to loosen when subjected to heat. It will be seen that this lining is open at the bottom—that is to say, it is not simply formed with a small opening to connect with the bore of the stump, but is left open to expose the wood of the bowl for a considerable area at the bottom thereof.

With the foregoing construction, it is found that the bowl and stump can be of much softer and more porous wood than heretofore, because the lining D, which is fire-proof, prevents the interior of the bowl from burning out. It is also found that by leaving the said lining open at the bottom there is less liability than heretofore of the bowl becoming clogged or fouled at the bottom thereof. For example, with pipes 80 having bowls and stumps made of brier wood, it is a common objection that the bottom of the bowl becomes clogged or fouled, sometimes with a sticky or viscous accumulation, which renders the pipe unfit for use. 85 My invention, however, is designed to overcome this difficulty, at least to a considerable extent, in addition to making it possible to use cheaper and softer wood without danger of burning out the bowl. For 90 example, with my invention, the bowl and stump can be made of oak, mahogany, birch or maple, or even a good quality of pine, the only requirement being that it be susceptible of a good external finish and not 95 liable to crack.

The inner bowl D is preferably tapered downwardly, and a chamber d is formed below the lower end of this inner bowl, which chamber is connected by the bore E through 100 the stump of the pipe to the bore of the push b and the stem B and the mouth-piece C, so that the smoke is drawn through the tobacco and passes through this chamber d before it reaches the mouth of the smoker. This, it 105 is found, in conjunction with the porous pipe-clay inner-bowl, tends to cool the smoke before it passes into the stem of the pipe. The outer bowl A is tapered downwardly inside thereof, to receive the tapered inner 110

bowl, and a layer of plaster of Paris and glue, forming the fire-proof cement F, is interposed between the two bowls. This not only holds the inner bowl in place, but also 5 serves to bind the fiber of the outer bowl together, it being borne in mind that the outer bowl is preferably made of wood which is soft as compared with the ordinary brier. In the use of birch or oak or other comparatively long and straight-grained wood for 10 this purpose, the bowl is made so that the grain of the wood extends horizontally of the bowl, toward the stem of the pipe, whereby the cutting operations to form the bowl are crosswise of the long grain of the wood, especially the boring out of the 15 interior of the bowl. By long grained wood is meant wood taken from the trunk of a tree in which the grain is long and comparatively straight as distinguished from the 20 short and irregular grain of certain kinds of hard wood and as distinguished from brier-wood which practically has no grain whatever. The cement E, therefore, serves to bind 25 the fiber of the wood together, so that the wood will not be liable to split, and the strong and substantial inner bowl D gives the entire bowl-construction the requisite solidity and strength, whereby even with soft wood the 30 pipe in its entirety is substantially as strong and solid as the ordinary brier-wood pipe, and no more liable to crack or split as the result of the heat.

There are various forms of commercial 35 pipe-clay which can be used for the inner bowl D, such as Scotch clay or magnesium clay, Florida clay, or other similar varieties of pipe-clay. Good results have been obtained by using what is known to the trade 40 as English cutty-clay. Some of the different clays can be mixed together, if desired, to produce the requisite porosity for the inner bowl. In any event, however, the inner bowl is formed separately, from pipe-clay 45 which is baked hard before it is inserted in the pipe, and the inner bowls thus manufactured are then cemented in the wood-bowls of the pipes, so that the pipe-clay and wood become permanently united, so that the 50 inner bowl will not fall out when heated.

The wood pipe—that is to say, the pipe made with a bowl and stump of wood, has become the standard and is more popular than any other form of pipe, and it is estimated that more wood pipes are sold and used than all other forms of pipe taken together. There are reasons for this, as the wood has certain advantages which are well recognized by both the manufacturers and 55 the users of pipes. On the other hand, the ordinary clay pipe, which is usually made of white pipe-clay, also possesses some advantages, as the bowl is porous and absolutely fire-proof at the same time, so that the 60 moisture in the tobacco is absorbed and does

not pass with the smoke to the mouth of the user. In other words, the clay pipe is usually dry and clean, whereas one difficulty with the ordinary brier pipe or pipe made from other wood, as heretofore constructed, 70 has been that the nicotin, along with the moisture in the tobacco, was not absorbed by the pipe, but to the contrary passed with the smoke through the mouth-piece of the pipe. My invention, therefore, combines in one 75 pipe the advantages of both the wood pipe and the clay pipe, and by the use of the pipe-clay inner bowl, the outer bowl can be of much softer and less expensive wood than is possible when the wood is directly exposed 80 to the combustion of the tobacco in the bowl. Thus the cost of manufacture is reduced, and a better and more satisfactory pipe is produced.

As the baked pipe-clay does not char or 85 burn, it is easy to clean the pipe by scraping it out with a knife. Wood pipes, even when made of brier-wood, will char to a certain extent and require "breaking-in," and in the first instance, and always to some extent, 90 the user will draw wood smoke into the mouth, along with the tobacco smoke. This is true, of course, of any pipe made of inflammable or combustible material, or material which will burn or char to any extent. 95 The baked pipe-clay, however, is absolutely non-combustible, and does not give off any smoke or odor which will pass with the tobacco smoke to the mouth of the smoker. An ordinary clay pipe, however, becomes 100 too hot to handle comfortably, but with the wood outer bowl this difficulty is obviated, as wood does not become so highly heated. Thus, as stated, the pipe combines the advantages of the clay pipe and the wood 105 pipe, but without the difficulties or disadvantages of either one.

It will also be seen that ordinary or comparatively soft wood, such as plain or straight-grained woods which may be employed in the construction of my invention, are much more porous and absorbent than brier wood, which latter, like other similar materials, is very hard and dense. It follows, therefore, that, in a pipe constructed 115 in accordance with my invention, a soft wood can be used which will absorb the nicotin and moisture while the smoke is passing from the bottom of the white pipe-clay inner bowl through the chamber d and through the bore e of the stump a and the stem of the pipe. As shown, the stump of the pipe is, of course, integral with the outer bowl, as is usual in wood pipes.

Thus by the use of cheap wood the invention not only accomplishes a substantial reduction in the cost of manufacture, but also, in combination with the porous pipe-clay inner bowl, the production of a superior 125 pipe. The relatively soft wood is not only 130

absorbent, producing a beneficial effect in the bottom of the bowl and in the stump of the pipe, by absorbing the moisture and the nicotin, but is also much lighter than brier wood and other similar materials heretofore employed in the manufacture of pipes. Thus, as stated, the invention contemplates the solving of the problem of the use of cheap wood, such as ordinary lumber, in the 10 production of what is really a superior pipe.

In the manufacture of the pipes, the wood bowls and stumps, when fully shaped, are then stained and finished. This is preferable to the staining and finishing of the 15 pipe after the inner white pipe-clay bowl is secured in place, because, should the pipe bowls then be immersed in the staining liquid, the porous pipe-clay inner bowls and linings would absorb so much of the staining liquid that one of the objects of the invention would be defeated, as the inner bowl in such case would not absorb the nicotin and moisture, at least not at first, and would, moreover, give off a vapor and odor which 20 would mix with the smoke and be offensive to the smoker.

As stated, the inner bowl D is preferably tapered downward, as in several ways this is better than a straight or cylindric inner 30 bowl, and for one thing it tends to prevent cracking of the wood. In the construction of pipes from different kinds of materials, the expansion and contraction of the materials must be taken into account, and it is 35 found that soft wood when combined with the white pipe-clay inner bowl, as shown and described, and when subjected to the heat and the moisture, will not result in detaching the inner bowl from the wood of the 40 outer bowl, but will retain the two materials (the comparatively soft and light wood and the hard but porous pipe-clay inner

bowl) firmly united and rigidly connected together.

What I claim as my invention is:—

45

1. A smoking pipe comprising an outer bowl of soft long grained wood, a bottomless inner bowl of porous baked pipe-clay, and a binder of cementitious material between the outer surface of the inner bowl 50 and the inner surface of the outer bowl to hold the inner bowl permanently in place, with the soft wood exposed immediately below the lower end of said inner bowl.

2. A smoking pipe comprising an outer 55 bowl of wood, a porous inner bowl of baked pipe-clay, and a binder of cementitious material between the outer surface of the inner bowl and the inner surface of the outer bowl to hold the inner bowl permanently in place, 60 said outer bowl being of long grained wood with the grain thereof extending transversely across the bowl toward the stem of the pipe.

3. A smoking pipe comprising an outer 65 bowl of soft absorbent wood, a porous inner bowl of baked pipe-clay, and a binder of cementitious material between the outer surface of the inner bowl and the inner surface 70 of the outer bowl to hold the inner bowl 75 permanently in place, said inner bowl being entirely open at the bottom thereof and terminating short of the bottom of said outer bowl to provide a chamber extending under the lower end of said inner bowl, and said outer bowl having an integral stump provided with a bore communicating with said chamber, so that with an outer bowl of soft wood the moisture will be absorbed while the smoke is passing from the bottom of the 80 inner bowl to the mouth-piece of the pipe.

Signed by me at Chicago, Illinois, this 20th day of September, 1916.

JACOB D. BURGER.
